(57) CLAIM

The ornamental design for a pot cover, as shown and described.

DESCRIPTION

FIG. 1 is a perspective view of a pot cover showing my new design;

FIG. 2 is a top view of the pot cover.

FIG. 3 is a side view of the pot cover.

FIG. 4 is a side view of the pot cover rotated 90 degrees with respect to its FIG. 3 orientation; and,

FIG. 5 is a bottom view of the pot cover.

The broken line showing of the brush-type applicator that extends down into the pot, and the pot itself, is for illustrative purposes only and forms no part of the claimed design.
